UNITED STATES PATENT OFFICE.

ANDREW GERMAN, OF SUMNER, WASHINGTON.

NON-REFILLABLE BOTTLE.

1,075,030.

Specification of Letters Patent.

Patented Oct. 7, 1913.

Application filed May 28, 1912. Serial No. 700,216.

To all whom it may concern:

Be it known that I, ANDREW GERMAN, a citizen of the United States, residing at Sumner, in the county of Pierce and State 5 of Washington, have invented new and useful Improvements in Non-Refillable Bottles, of which the following is a specification.

This invention is an improved non-refillable bottle and consists in the construction, 10 combination and arrangement of devices hereinafter described and claimed.

The object of my invention is to provide a bottle of improved and novel construction which can not be filled excepting from the 15 bottom and can not be refilled except by leaving evidence of such fact, and, hence, is proof against being fraudulently refilled.

In the accompanying drawing:—Figure 1 is a vertical central sectional view of a non- 20 refillable bottle constructed in accordance with my invention. Fig. 2 is a detail sectional view of the same on a plane at right angles to that of Fig. 1 and showing a portion of the bottom of the bottle. Fig. 3 is 25 a detail sectional view of the upper portion of the bottle after the integral stopper cap has been broken off.

My improved bottle 1 may be blown or molded in the usual way and is preferably 30 made of glass. In accordance with my invention, the mouth and neck of the bottle are formed around the stopper 2 so that the mouth 3 of the bottle is formed or provided with an integral cap 4 which extends 35 around and also extends over and across the outer end of the stopper so that in the manufacture of the bottle the stopper is completely embedded in the mouth thereof and within the cap. The wall of the cap is 40 formed at the point where it joins the mouth of the bottle with an exterior annular groove 5, whereby the wall of the cap is weakened at the point 6 and, hence, the cap is made frangible at that point and may be 45 readily broken off, as shown in Fig. 3, so as to expose the outer portion of the stopper when the contents of the bottle are to be used.

Any suitable method within the skill of 50 glass workers may be employed for forming the mouth and neck of the bottle around the stopper. For instance, the cap may be formed separately from the bottle and then fused thereto and united integrally there- 55 with after the stopper has been inserted.

The bottom 7 of the bottle is bell-shaped

and in accordance with my invention is formed with an opening in one side leading into the interior of the bottle, there being a channel 9 in the under side of the central portion of the bottom and which communicates with and forms the inlet for the opening 8. This channel is formed with overhanging walls 10 which, in the form of the invention here shown, are indicated as converging downwardly.

The bottle is filled from the bottom through the channel 9 and opening 8, the stopper being, as hereinbefore stated, longitudinally and permanently embedded in the mouth and neck of the bottle. After the bottle has been filled the channel 9 is then filled with some suitable plastic material such as cement to form a plug 11 which permanently closes the inlet channel and after 75 it is hardened cannot be removed without betraying the fact, thus preventing the bottle from being surreptitiously refilled. In practice, a seal indicated at 12 can also be employed which may be fastened on the bottom over the said plug.

Owing to the location of the channel 9 in the underside of the central portion of the bell bottom, and the provision of the opening 8 which extends through one side 85 of the bell bottom, there is a shoulder formed in the channel and at the outer end of the opening 8, which shoulder forms a stop for the cement filling and causes the cement filling to become compacted at said 90 shoulder and enables the use of a cork in the opening 8 to be dispensed with.

In order to use the contents of the bottle, the integral cap must first be knocked off as in Fig. 3 so as to expose the outer portion of the stopper, and the stopper may be 95 then withdrawn in the usual manner and the contents of the bottle poured out. The breaking off of the frangible cap also indicates that the bottle has been used and, 100 hence, it cannot be refilled, without giving evidence of such fact.

While I have herein shown and described a preferred form of my invention, I would have it understood that changes may be 105 made in the form, proportion and construction of the several parts without departing from the spirit of my invention and within the scope of the appended claim.

I claim:—

A bottle having a bell bottom and a channel arranged transversely in the lower side

110

2 of the bell bottom and having overhanging walls, the bell bottom being further provided with a tubular portion projecting from the inner end of the channel through 5 one side of the bell bottom and into the bottle, the said tubular portion forming a filling opening and also forming a shoulder at the outer end of the filling opening and arranged in the channel, and a plastic plug 10 in the channel, compacted against the

shoulder at the outer end of the filling opening and held in place by the overhanging walls of the channel.

In testimony whereof I affix my signature in presence of two witnesses.

ANDREW GERMAN.
